Patented Sept. 6, 1887.

UNITED STATES PATENT OFFICE.

WILLIAM H. APPLETON, OF NEW YORK, N. Y.

MACHINE FOR ROLLING SEAMLESS TUBES.

SPECIFICATION forming part of Letters Patent No. 369,311, dated September 6, 1887.

Application filed December 22, 1886. Serial No. 222,263. (No model.)

To all whom it may concern:

Be it known that I, WILLIAM H. APPLETON, a citizen of the United States, and a resident of the city, county, and State of New York, have invented certain new and useful Improvements in Machines for Rolling Seamless Tubes, Pipes, and other Hollow Articles from Hollow Ingots, of which the following is a specification.

10 *My improvements, while capable of use in part with certain forms of what are known as "universal rolling-mills," or those in which a pair of vertical and a pair of horizontal rolls are employed, are designed more especially for application to the forms of machine illustrated in Letters Patent of the United States numbered 278,340 and 325,938, respectively, to which reference may be had.*

15 *In the construction of universal rolling-mills prior to the date of the patents aforesaid it had been the custom to support the under roll of the horizontal pair in fixed bearings, or in bearings which were incapable of any vertical adjustment, and to effect the reduction of the material being operated upon by adjusting the upper roll of such pair toward the under roll by means of screws or otherwise, one or both of the rolls of the vertical pair being similarly adjusted toward the other or toward each other, as the case might be. The under roll of the horizontal pair, being thus mounted in fixed or stationary bearings, with no means provided to raise or lower it, as a consequence always remained permanently at the same elevation, and the rolls or bed by which the material being reduced was supported and carried to and away from the reducing-rolls were or was similarly mounted and were or was incapable of any adjustment to a higher or lower*

20 *elevation.*

25 *The construction and arrangement of parts as thus described, while advantageous in rolling-mills employed for rolling solid articles—such, for instance, as plates, square bars, &c.—are incapable of use for rolling seamless tubes, pipes, and other tubular articles in which a stationary mandrel is employed, as no provision is made therein for maintaining each of the rolls at the same distance from the axis of the mandrel, or from a central line passing between them, as in the others, during the various adjustments thereof necessary to the*

reduction of the material and the production of the finished article.

25 *In the Letters Patent hereinbefore referred to this last-mentioned objection was partially overcome by mounting both the upper and under rolls of the horizontal pair, as well as both of the rolls of the vertical pair, in adjustable bearings and providing each of said bearings with a screw, whereby not only could both the vertical rolls be adjusted toward and away from the axis of the mandrel, but also both of the horizontal rolls as well. This organization of mechanism, while rendering capable the adjustment of the rolls to maintain the relation between the grooves therein and the axis of the mandrel, has been found defective, principally because of the fact that each of the said screws is independent of and unconnected with the others, and in the adjustment of the rolls each of said rolls is adjusted by itself apart from the others, requiring not only much time therein, but great difficulty was experienced in moving them all at the same distance to bring them into proper relation with respect to the mandrel.*

30 *The objects of my invention are therefore, first, to overcome this defect and to provide means whereby the adjustment of both the rolls in the vertical and horizontal pair may be effected simultaneously and at precisely the same distance; second, to furnish improved means for maintaining the free end of the mandrel in proper relation to the reducing-rolls when the tube or other article being reduced is clear from such rolls and has been either forced upon the mandrel or withdrawn therefrom; third, to provide means for adjusting the rolls which support and carry the material being reduced to and away from the reducing-rolls to maintain them in proper relation with respect thereto, and, fourth, to devise means whereby the flexure or bending of the mandrel may be prevented while the pipe or other article being rolled is forced upon it in the operation of rolling.*

35 *To this end my invention consists in the mechanism whereby these results are accomplished, the nature and distinguishing characteristics of which will be best understood by reference to the accompanying drawings, in which—*

40 *Figure 1 represents a side elevation of a por-*

tion of a universal rolling-mill with my improvements applied thereto, a portion of the standards or housings being broken away to show parts beyond, and the cylinders for operating the adjusting-shafts being omitted; Fig. 5, a plan view thereof, with the cylinder for operating the adjusting-shafts in position; Fig. 2, a plan view thereof, with the cylinder for operating the adjusting-shafts in position; Fig. 3, a sectional elevation of a slightly-modified form of mandrel and its arrangement with other parts with which it co-operates. Fig. 4 is a section taken on the line $x-x$ of Fig. 3, and Fig. 5 a detail illustration of the relation of the supporting-rolls with respect to the reducing-rolls during the operation of rolling.

15 In all the figures similar letters designate corresponding parts.

A A' indicate standards or housings having suitable guideways, $a b$, formed therein for the reception and accommodation of boxes or bearings $c c' d d'$, and B B' C C' are circumferentially-grooved reducing-rolls carried thereby, the former of which are arranged upon horizontal axes and the latter upon vertical axes, all as shown.

25 D D' E E' indicate screws by means of which the various rolls are adjusted toward and away from the article being rolled, and F the stationary mandrel over and from which such article is alternately forced and withdrawn 30 during the rolling operation.

The parts as thus far described are or may be of the forms illustrated in the Letters Patent above noted, and their arrangement may be substantially the same as that shown therein. 35 The screws D D' E E', however, while constructed and arranged in substantially the same way as those shown in said patents, are each provided at its outer end with a plain portion of considerable length, from which the 40 screw-thread is omitted, as shown at $e e$ in Figs. 1 and 2.

F F' G G' indicate gear and sprocket wheels, respectively mounted upon these plain portions, and being connected to them by means 45 of groove-and-feather connection $f f'$ in such manner as to permit of the movement of the latter longitudinally through the former in effecting the adjustment of the rolls, while at the same time compelling them, with their 50 screws, to revolve with the gears and sprocket-wheels as such devices are rotated.

The gears F F' are of the ordinary spur form, and are mounted upon the plain portions of the screws D D', respectively. The 55 gears G are of the bevel form, and are mounted upon the plain portions of the screws E, while the sprocket-wheels G' are similarly carried by the plain portions of the screws E'. The gears-wheels F F' are of precisely the same diameters and mesh with spur-gears H and H', respectively fixedly secured upon the vertical shafts I I', which are arranged in suitable bearings, $g g'$, upon opposite sides of the machine. The gears H H' are also of the same diameters, 60 so that upon rotating either of said shafts the gears F F', meshing with the gears carried by

it, will both be revolved through precisely the same angular distance. The effect of this will be to cause the rotation to the same extent of the screws upon which such gears F F' are mounted, and the consequent adjustment toward and away from the other to precisely the same distance of each of the boxes or bearings $c c'$, upon which such screws operate. The sprocket-wheels G' upon the plain portions e 70 of the screws E' are each preferably connected to and rotated from the bevel-gear G, located upon its respective side of the machine, through the intervention of a second sprocket-wheel, K, of the same diameter as the first, secured to 75 or formed on the hub of said gear, and a chain, L, passing over both of said sprocket-wheels, the arrangement being such that upon rotating the gear G the sprocket-wheel G' will be revolved through precisely the same angular 80 distance as said gear. Meshing with each of the bevel-gears G, on opposite sides of the machine and of the same diameter, is a bevel-gear, M, which is secured to the upper end of an inclined shaft, N, mounted in suitable bearings, $i i'$, bolted or otherwise secured to the standards or housings A A', and carrying at its lower end a second bevel-gear, O, which meshes with a third bevel-gear, P, of the same 85 diameter as itself, secured to the vertical shaft 90 I or I'. 95

By the means as thus described it will be seen that upon rotating either of the vertical shafts I or I' the various screws located on the same side of the machine as such shaft 100 will be all rotated to precisely the same extent, and the bearings in connection with which they operate will all be adjusted simultaneously toward and away from each other to exactly the same distance, the direction of 105 adjustment depending upon the direction in which said shaft is revolved. Various means may be employed for rotating these shafts—as, for instance, a hand-wheel secured thereto or other suitable device—and the two shafts I I' 110 may, if desired, be connected so as to revolve in unison and cause the adjustment of all the bearings upon both sides of the machine, and with them all the reducing-rolls simultaneously, by means of a chain and sprocket-wheels or by a cross-shaft and bevel-gears. 115

The arrangement of parts whereby the two shafts are revolved in unison is the one I adopt in practice; but instead of rotating said shafts by hand I prefer to operate them by power, 120 and for this purpose I secure to the lower end of each of said shafts a spur-gear, P', which meshes with a rack, R, extending transversely of the machine, and being connected to the end of a piston-rod, S, which, with a suitable piston, is fitted to work in the steam-cylinder T. The gears P' P' are of precisely the same diameter, and the rack R, which meshes with them, is of such length as to rotate them several times in being reciprocated the length of 125 its movement in either direction, the number of rotations of said gears by one reciprocation

of the rack being sufficient to effect the greatest range of adjustment of the reducing-rolls that will be required in any case.

The reciprocation of the rack, as will be understood, is effected from the steam-cylinder T through the medium of the piston-rod S and the piston thereon, which cylinder is of proper length to cause said rack to travel to its extreme limit of movement in either direction; but instead of being constructed as is common with steam-cylinders generally, the ordinary steam ports and chest are omitted, and in lieu thereof it is provided with induction-pipes k' and eduction-pipes l' l'', &c. The eduction-pipes l' l'', &c., which are in practice preferably constructed of somewhat greater diameter than the induction-pipes k' k'', are arranged at certain distances apart, dependent upon the amount of reduction that is to be given to the material being operated upon at each passage between the reducing-rolls, and are, with the induction-pipes k' k'', provided with suitable valves, m m', whereby the flow of steam or other elastic medium to and from the cylinder and the amount of movement to be given to rack R at any particular time may be governed. For instance, the piston and the rack being at the extreme limit of their movement toward the rear of the cylinder, and the reducing-rolls B B' C C' being withdrawn from each other and from the axis of the mandrel to their greatest extent, with all the valves m m' in the induction and eduction pipes closed, and it being desired to adjust the rolls toward each other a certain distance, the valve of the eduction-pipe corresponding to that distance—for example, the valve in eduction-pipe l—is opened and the steam admitted to the cylinder through the induction-pipe k by opening the valve m therein. The steam thus entering the cylinder will cause the piston, the piston-rod, and the rack to move forward with it, rotating the vertical shafts I I' by the engagement of the rack with the gears P' P' thereon, and, through the various screws D D' E E', cause each of the reducing-rolls to approach the other through precisely the same distance. The continued flow of steam causes the piston to move forward until it has passed the inner end of the eduction-pipe l, when the steam will be discharged through said pipe and the further movement of the piston arrested. The valve in the induction-pipe k is then closed and the adjustment is completed. If, now, it be desired to adjust the reducing-rolls toward each other still farther—as, for instance, to the distance corresponding to the eduction-pipe l'—the valve m' in that eduction-pipe is opened and the steam admitted to the cylinder through the pipe k, when the same operations will be repeated and the reducing-rolls adjusted, as before, and so on until the piston-rod has passed the last eduction-pipe next to the forward end of the cylinder. The piston is then forced back to its starting-point, carrying with it the rack and the various reducing-rolls, by closing all the valves in

the eduction-pipes with the exception of that in the pipe l, which is opened, and admitting steam into the other end of the cylinder through the induction-pipe k', which can be effected by opening the valve m therein. By this arrangement of parts, as will be seen, I am enabled to adjust the reducing-rolls by power either toward or away from each other, and at the same time to maintain them in their proper relation with respect to the axis of the mandrel and with each other, the amount and direction of adjustment of said rolls depending at all times upon the arrangement of the eduction-pipes l' l'', &c., in the cylinder T, and upon the order in which their valves and those in the induction-pipes k' k'' are opened and closed.

The mandrel F² is anchored or supported at its rear end by any suitable or well-known means. I prefer, however, to employ the device shown in the later of the patents herein-before referred to as being the most simple and efficient for this purpose; and in order to support its front or free end and hold it in proper central relation with respect to the grooves in the reducing-rolls for entering the aperture in the article being rolled when said article is presented to the reducing-rolls, I make use of the supporting-roll V, upon which it rests. This supporting roll is journaled in the free end of an arm, n, which is jointed or hinged at its lower end to the stock or bar n', fitted in a suitable holder, p, in which it is vertically adjustable by means of a screw, p'. The arm n, when the mandrel is free from the article being rolled, or when such article has been forced upon it to such a distance that its rear end has passed beyond the point where said arm is located, is in a vertical position, with the supporting-roll V resting in a notch or depression, q, formed in the mandrel, it being held normally in that position by a spring, r, acting upon a segmentally-shaped cam, r', secured to its side, as shown in Fig. 3. This arm, however, while being thus held, is capable of a swinging movement either to the right or left therefrom, as shown in Fig. 1, to carry it and the supporting-roll V down and away from the mandrel F², to permit of the article X² being rolled passing on over the same or of being withdrawn therefrom; and in the operation of rolling this swinging movement will be given to said arm by the forward end of the article being rolled striking the roll V and carrying it forward with the arm until such devices are swung down below and out of the way of said article, the return of these parts to their normal positions being effected after its passage by the spring r and cam r'. The movements of the arms, as thus described, take place with every passage on or off the mandrel of the article being rolled, the hinge or joint by means of which it is connected to the stock or bar p permitting of its movement in both directions with equal facility.

X X indicate the rolls by means of which the article being rolled is supported and carried to and away from the reducing-rolls, and

X' X' stands in which they are supported. These rolls are preferably constructed with a circumferential groove in their faces, of circular form, and instead of being mounted in fixed bearings, as has been the custom heretofore, they are journaled in bearings s s, which are capable of vertical adjustment in suitable guideways, t t, formed in or upon the stands X' X'. Depending from the under side of each of these bearings is a sleeve-like portion, s', having formed axially therein a screw-threaded aperture, s², in which is fitted to work the upper end of a screw-rod, t', by means of which said bearings and the journal of the roll carried thereby may be adjusted. The several screw-rods t' t' may be rotated by any convenient means. I prefer, however, to connect them in sets or groups, those, for instance, on one side of the machine, as at the right of the reducing-rolls in Fig. 1, constituting one set, and those on the other side, or left, of the reducing-rolls in said figure making up the other, and to rotate the rods of each set in unison independently of the others. For this purpose I provide each of said screw-rods at its lower end with a bevel-gear, u, which meshes with a corresponding bevel-gear, u', mounted upon the adjusting-shafts v v. The bevel-gears on the screw-rods t' t' are all of the same size, as are also the corresponding gears on the adjusting-shafts v v.

Various means may be employed for connecting and rotating the adjusting-shafts appertaining to each set of screw-rods. The mechanism adopted by me, however, for this purpose consists of a spur-gear, y, mounted on each of said shafts, and a rack, Z, intermeshing therewith, the said rack being arranged transversely of the machine and being reciprocated from the steam-cylinder Y through the intermediary of a piston and a piston-rod, y'. It will thus be seen that upon reciprocating either of the racks the adjusting-shafts v v, operated therefrom, will be rotated, and the rolls of the set to which they belong will be adjusted either up or down through the medium of the screw-rods and gears, according as the rack is reciprocated in one or the other direction.

The steam-cylinders Y Y, for operating each of the racks Z Z, are similar in all respects to the cylinder T, for adjusting the reducing-rolls, and the induction-pipes z z', eduction-pipes z' z'', &c., and the valves y² and y³ are all arranged and operated in precisely the same manner as the like parts shown in connection therewith.

The rolls X X of either set being in their lowest position, the piston in the cylinder Y withdrawn to the rear end of the latter, and it being desired to adjust said rolls to a certain height, the valve in the eduction-pipe corresponding thereto will be opened—as, for instance, z²—and steam admitted to the cylinder through the induction-pipe z by opening the valve y³, and the piston, with its rod y', will be forced forward, carrying with it the

rack Z, which, through the gears and adjusting-shafts v v, will revolve the screw-rods t' t' and adjust the rolls to the required position. 7C The valve y³ will then be closed and the required adjustment is effected. If, now, it be desired to adjust the rolls to a still higher altitude, the valve in the eduction-pipe corresponding to that elevation will be opened, the steam admitted through the induction-pipe z, as before, and the new adjustment attained, and so on until the piston has been carried past the last eduction-pipe, z⁹. The piston and the rolls X X will then be returned to their original position by closing the valves in all of the eduction-pipes with the exception of that in the pipe z², which will now be opened, and admitting steam to the other end of the cylinder through the induction-pipe z' by opening the valve y³ therein. 80

The cylinders Y Y in practice are constructed of such length as to cause the same range of adjustment of the rolls X X as is given to the reducing-rolls B B' C C' by the cylinder 90 T; and in order to provide for adjusting the former rolls with reference to the latter the eduction-pipes in the cylinders Y Y are arranged in such relation to the eduction-pipes in the cylinder T that upon opening the valve 95 in any one of said pipes of either of the former cylinders and admitting steam to said cylinder in rear of the piston the rolls X X, operated therefrom, will be adjusted to precisely the same height as will be attained by the under roll, B', of the reducing-rolls upon opening the valve in the corresponding eduction-pipe in the cylinder T and admitting steam similarly to that cylinder. In other words, 100 upon adjusting the reducing-rolls to any position determined by any one of the eduction-pipes in the cylinder T the rolls X X will be adjusted to precisely the same height as the under roll, B', of the horizontal pair thereof by 105 opening the valve in the corresponding eduction-pipe in either of the cylinders Y Y and admitting steam to that cylinder. The eduction-pipes of these several cylinders being thus arranged, the adjustment of the supporting-rolls with respect to the reducing-rolls is 115 readily accomplished.

In rolling a tube or other article the reducing-rolls will first be withdrawn to their utmost limit and the supporting-rolls drawn down to their lowest point, in which position 120 the upper surfaces of the latter will be in a line with the upper surface of the under reducing-roll, B', this being insured at all times when thus retracted by means of the set-screws l, passing through the cylinder-heads 125 and abutting against the rear sides of the pistons. The heated ingot is then placed upon the set of supporting-rolls to the left of the reducing-rolls. The reducing-rolls are next adjusted toward each other by means of the 130 steam-cylinder T, and the set of supporting-rolls to the right of the reducing-rolls are adjusted upward by means of their cylinder until their upper surface is brought into line

with the upper surface of the under reducing-roll, B'. The reducing-rolls are then started and the heated ingot drawn in between them and over the mandrel, the relation of the various rolls—both reducing and supporting—at this time being best shown in Fig. 5. The ingot having passed entirely through the reducing-rolls, the latter are again adjusted toward each other, the set of supporting-rolls on the left of the reducing-rolls is adjusted upward by means of their steam-cylinder until their upper surface is on a line with the upper surface of the under reducing-roll, B', and the revolution of the reducing-rolls is now reversed. The effect of this will be to withdraw the ingot from the mandrel and carry it back between said rolls, after which the reducing-rolls will be again adjusted and reversed and the ingot passed through between them, as before, and so on, the set of supporting-rolls toward which the ingot is carried being always adjusted to the same height as the under reducing-roll, B'.

I sometimes find it convenient to rotate the supporting-rolls positively from the reducing-rolls, and for this purpose I employ the chain or belt 2, which passes over a grooved pulley or sprocket-wheel, 3, on the journal of the under roll, B', and around a similar pulley or wheel on the journal of each of the adjusting-rolls, as shown at 4. By this means, as will be seen, a positive motion is given to the supporting-roll in the same direction as is imparted to the reducing-roll.

I have shown in the drawings only one supporting-roll in the set to the left of the reducing-rolls, and but two of such rolls in the set at the right thereof; but it is to be understood that in actual practice these numbers will be increased and each set be made to include quite a number of such devices.

In Figs. 1 and 3 I have shown the devices by means of which the flexure or bending of the mandrel is prevented when the tube or other article is being forced thereon. These devices consist of suitable guideways, 5, secured to the stands X' X', both above and below the mandrel F², and have fitted in each a stock or bar, 6, to the end of which is hinged or jointed an arm, 7, carrying in its free end a roll, 8. These rolls are provided in their periphery with a groove of such a contour as to accurately fit the surface of the mandrel against which they bear. When the mandrel is free, or when the tube or other article has not been forced thereon sufficiently far as to arrive opposite these rolls, the arms 7 carrying them are in a vertical position, as shown at the extreme right of Fig. 1, and the mandrel is held not only from vertical but also from lateral flexure. As soon, however, as the forward end of the tube or other article arrives opposite any one of these rolls, it strikes the same and, through it, swings its carrying-arm back away from the mandrel sufficiently far to permit of the tube or other article being forced thereover. The arms are then held in this position

until such tube or other article is withdrawn from the mandrel, when they swing back into a vertical position, and so remain until again swung away thereby. If desired, a light flat spring, 9, or, in place thereof, a strap and weight, may be employed for returning the arm to its vertical position after having been swung therefrom; and in order to adapt these devices to mandrels of different sizes, I prefer to make the stocks 6 adjustable in guideways 5, and employ set-screws 10 for effecting their various adjustments.

In the machine above described the mandrel F² has been of the form of that illustrated 80 in the later of the patents above alluded to; but in Fig. 3 I have shown the mandrel pictured and described in the earlier of said patents employed in lieu thereof, the same being provided with the rolls 11 11, for contact with 85 the interior of the pipe or other article being rolled, and the pipes 12 and ducts 13, by means of which water may be conveyed to and discharged upon said rolls to lubricate them when in operation.

From the foregoing it will be observed that I produce a machine for rolling tubular or hollow articles in which the adjustment of all the reducing-rolls necessary to the production of the finished articles is effected simultaneously and by power, and, in addition thereto, provide means whereby not only the rolls which support and carry the article being rolled to and away from the reducing-rolls may be maintained in their proper relation with respect to the latter at all times, but also whereby the mandrel may be prevented from flexure or bending when such article is being forced thereon, and its forward or free end be held in central relation with respect to the 105 grooves in said reducing-rolls when the article being rolled is forced entirely thereupon or is removed therefrom.

While I have shown and described the best means contemplated by me for carrying my 110 invention into practice, I wish it distinctly understood that I do not limit myself strictly thereto, as it is obvious that the details thereof may be modified in various ways without departing from the spirit thereof.

Having now described my invention and one way in which it is or may be carried into effect, what I claim as new, and desire to secure by Letters Patent, is—

1. The combination, with the pair of vertical and the pair of horizontal rolls of a universal rolling-mill and devices for adjusting each of said rolls toward and away from its fellow roll, of mechanism for connecting such adjusting devices, whereby the adjustment of all of said rolls may be simultaneously effected and to the same extent, substantially as described.

2. The combination, with the pair of vertical and the pair of horizontal rolls and bearings and screws for each of said rolls, of mechanism for connecting such screws, whereby

the rolls of both of said pairs may be adjusted simultaneously toward and away from its fellow roll, substantially as described.

3. The combination, with the pair of vertical and the pair of horizontal rolls, the bearings and screws for each of said rolls, the housing in which such rolls, bearings, and screws are mounted, a shaft arranged upon each side of the housing, and devices for connecting said screws with the shaft on their respective sides of the housing, of mechanism for rotating said shafts in unison to cause the simultaneous adjustment of all the rolls, substantially as described.

15 4. The combination, with the pair of vertical and the pair of horizontal reducing-rolls, the bearings and screws for each of said rolls, the housing in which such rolls, bearings, and screws are mounted, a shaft arranged upon each side of the housing, and devices for connecting said screws with the shaft on their respective side of the housing, of a cylinder provided with induction and eduction pipes, a piston and a piston-rod, a rack, gears mounted 25 on said shafts and meshing with such rack, and suitable valves for the induction and eduction pipes, substantially as described.

5. The combination, with the screws D D', E E', the gears F F', the shaft I, provided with 30 the gears H H' P P', the gear G, the sprocket-wheels G' K, the chain L, and the shaft N, provided with the gears M O, of the cylinder T, provided with induction-pipes k k', eduction-pipes l l', &c., the piston-rod S and piston 35 thereon, the rack R, and suitable valves for the induction and eduction pipes, substantially as described.

6. The combination, with the mandrel F², the holder p, and stock or bar n', of the arm n, 40 the roll V, journaled in its upper end, the segmentally-shaped cam r', and the spring r, substantially as described.

7. The combination, with the horizontal rolls of a rolling-mill and mechanism for adjusting each of said rolls toward and away 45 from the other, of devices for supporting the article being rolled and means for rendering these devices vertically adjustable, whereby said devices may be adjusted with relation to 50 the under of such horizontal rolls as it is raised or lowered, substantially as described.

8. The combination, with the pair of vertical and the pair of horizontal reducing-rolls of a universal rolling-mill and mechanism for 55 adjusting each of the rolls of said pairs toward and away from its fellow roll, of devices for supporting the article being rolled and

mechanism for rendering these devices vertically adjustable, whereby said devices may be adjusted with respect to the reducing-rolls as 60 they are adjusted toward and away from each other, substantially as described.

9. The combination, with the pair of vertical and the pair of horizontal reducing-rolls and mechanism for simultaneously adjusting 65 the rolls of each of said pairs toward and away from its fellow roll, of rolls for supporting the article being rolled and mechanism for vertically adjusting these latter rolls, whereby to bring them into proper relation 70 with respect to the reducing-rolls as they are adjusted toward or away from each other, substantially as described.

10. The combination, with the pair of vertical and the pair of horizontal reducing-rolls 75 of a universal rolling-mill and mechanism for simultaneously adjusting the rolls of each of said pairs toward and away from its fellow roll, of rolls for supporting the article being rolled, stands in which these last-mentioned 80 rolls are mounted, and mechanism for vertically adjusting said rolls, whereby to bring them into proper relation with respect to the reducing-rolls as they are adjusted toward or away from each other, substantially as 85 described.

11. The combination, with the stands X' X', the supporting-rolls X X, the bearings s s, screw-rods t t', having the gear u on each of their lower ends, and the shafts v v, provided 90 with the gears u' u' of the cylinder Y, provided with the induction-pipes z z' and eduction-pipes z² z³, &c., the piston-rod y' and piston thereon, and the rack Z, whereby the supporting-rolls of either set may all be adjusted 95 simultaneously and by power, substantially as described.

12. The combination, with the mandrel, of devices for acting against the same at different points around its circumference to prevent it from bending or flexure in any direction, substantially as described. 100

13. The combination, with the mandrel F² and the stand X', having the guideway 5 secured thereto, of the stock or bar 6, the hinged arm 7, and the wheel 8, as and for the purpose set forth.

In testimony whereby I have hereunto set my hand this 20th day of December, 1886.

WILLIAM H. APPLETON.
